UNITED STATES PATENT OFFICE.

DAVID CLUMP AND WILLIAM HOFMEISTER, OF ST. LOUIS, MISSOURI.

SMOKE-CONSUMER.

SPECIFICATION forming part of Letters Patent No. 701,296, dated June 3, 1902.

Application filed February 15, 1902. Serial No. 94,227. (No model.)

To all whom it may concern:

Be it known that we, DAVID CLUMP and WILLIAM HOFMEISTER, of the city of St. Louis, State of Missouri, have invented certain new and useful Improvements in Smoke-Consumers, of which the following is a full, clear, and exact description, reference being had to the accompanying drawings, forming a part hereof.

10 Our invention relates to smoke-consuming furnaces; and it consists of the novel features herein shown, described, and claimed.

Our object is to construct a boiler-furnace or the like in such a way that it will give off 15 the least possible smoke; and our invention consists of a furnace comprising an ash-pit, side walls extending upwardly from the ash-pit, a bridge-wall or back wall extending straight up from the ash-pit, the upper edge 20 of said bridge-wall projecting forwardly over the grate, a grate mounted above the ash-pit between the side walls and in front of the bridge-wall, perforated pipes mounted in the side walls a suitable distance above the grate 25 and in the projecting portion of the bridge-wall, the openings in said pipes discharging inwardly over the fire upon the grate, steam air-injectors connected to said pipes, and means of turning said pipes in their bearings 30 as required to adjust the direction of the discharge into the fire.

Figure 1 is a vertical longitudinal section of a furnace constructed in accordance with the principles of our invention. Fig. 2 is a 35 horizontal section above the grate. Fig. 3 is a cross-section of one of the injector-pipes.

Referring to the drawings in detail, our improved smoke-consuming furnace consists of the ash-pit 5, the side walls 6 and 7, extending upwardly from the ash-pit, the bridge-wall 8, extending upwardly behind the ash-pit and having the forwardly-projecting portion 9 at its upper end; the grate 10, mounted above the ash-pit, the perforated injector-pipes 11 and 12, mounted in the side walls a suitable 45 distance above the grate, and the perforated injector-pipe 13, mounted in the forwardly-extending projection 9 of the bridge-wall, the perforations 14 of said injector-pipes discharging horizontally inwardly 50 over the fire, and the steam air-injectors 15, 16, and 17, connected to the injector-pipes 11,

12, and 13, respectively. The pipes 11, 12, and 13 are mounted to be rotated in their bearings as required to change the direction 55 of the discharge-openings 14. This rotary motion may be provided by making either the joint 18 or the joint 19 of each injector loose, so that the injector-pipe may be screwed one way or the other as required to attain 60 the required direction of the discharge-openings. The injectors 15, 16, and 17 each consist of a nipple 20, connected to the steam-pipes 21 and having a reduced discharge-opening 22, the nipple 23, formed integrally with the nipple 20 and in alignment therewith, and the nipple 24, formed integrally with the nipples 20 and 23, said nipple 24 extending backwardly and outwardly at an angle of about forty-five degrees, so that steam admitted through the 70 pipes 21 and discharged through the reduced openings 22 into the nipples 23 will draw air through the nipples 24 and force the mixture of air and steam into the injector-pipes 11, 12, and 13 and discharge said air and steam 75 through the perforations 14 into the fire. The adjustment of the direction of the discharge from the perforations 14 is illustrated in Fig. 3. Thus it will be seen that air and steam is injected into the fire from three sides, and the 80 air passing through the draft-openings 25 is on the fourth side and passes over the fire. The result is greatly-improved combustion and the total elimination of smoke as soon as the fire is properly started and the equilibrium 85 established.

We claim—

1. A smoke-consuming furnace comprising the ash-pit 5; the side walls 6 and 7 extending upwardly from the ash-pit; the bridge-wall 8 extending upwardly behind the ash-pit and having the forwardly-projecting portion 9 at its upper end; a grate mounted above the ash-pit; the perforated injector-pipes 11 and 12 mounted in the side walls a suitable 95 distance above the grate; the perforated injector-pipe 13 mounted in the forwardly-extending projection 9 of the bridge-wall; and the steam air-injectors 15, 16 and 17 connected to the injector-pipes 11, 12 and 13, said 100 injector-pipes being independently rotatable in their bearings, substantially as specified.

2. A smoke-consuming furnace comprising the ash-pit 5; the side walls 6 and 7 extend-

ing upwardly from the ash-pit; the bridge-wall 8 extending upwardly behind the ash-pit and having the forwardly-projecting portion 9 at its upper end; a grate mounted above 5 the ash-pit; the perforated injector-pipes 11 and 12 mounted in the side walls a suitable distance above the grate; the perforated injector-pipe 13 mounted in the forwardly-extending projection 9 of the bridge-wall; and 10 the steam air-injectors 15, 16 and 17 connected to the injector-pipes 11, 12, and 13; said injector-pipes being independently rotatable in their bearings; each of said steam air-injectors comprising a nipple 20 connected

to the steam-pipes and having a reduced discharge-opening 22, the nipple 23 formed integrally with the nipple 20 and in alinement therewith, and the nipple 24 formed integrally with the nipples 20 and 23, said nipple 24 extending backwardly and outwardly at 20 an angle of about forty-five degrees.

In testimony whereof we affix our signatures in presence of two witnesses.

DAVID CLUMP.

WILLIAM HOFMEISTER.
